(57) **CLAIM**

The ornamental design for a inflatable paint booth, as shown and described.

DESCRIPTION

FIG. 1 is a front elevational view of inflatable paint booth; FIG. 2 is a back side elevational view thereof; FIG. 3 is a left view thereof; FIG. 4 is a right view thereof; FIG. 5 is a top view thereof; FIG. 6 is a bottom view thereof; and, FIG. 7 is a perspective view hereof.

The broken line showing is for the purpose of illustrating portions of the inflatable paint booth which form no part of the claimed design.
